UNITED STATES PATENT OFFICE.

OLIVE L. FLETCHER, OF PERU, INDIANA, ASSIGNOR TO PERU ELECTRIC COMPANY,
OF PERU, INDIANA, A CORPORATION OF INDIANA.

STRAIN-INSULATOR.

1,028,104.

Specification of Letters Patent.

Patented June 4, 1912.

Application filed August 16, 1911. Serial No. 644,432.

To all whom it may concern:

Be it known that I, OLIVE L. FLETCHER, a citizen of the United States, residing at Peru, in the county of Miami and State of Indiana, have invented new and useful Improvements in Strain-Insulators, of which the following is a specification, reference being had to the accompanying drawings, forming a part thereof.

10 The purpose of this invention is to provide an improved form of strain insulator for use in connection with electrical wiring.

It consists of the features of construction shown and described in the drawings as 15 indicated in the claims.

In the drawings:—Figure 1 is a medial section of the insulator taken as indicated at line 1—1 on Fig. 2. Fig. 2 is a side elevation of the same. Fig. 3 is an end elevation of the insulator, being a section taken as indicated at line 3—3 on Fig. 2.

The drawings illustrate a form of insulator, A, particularly adapted for use where two wires, B and C, are connected, 25 one of which is in contact or liable to come in contact with one of the wires of an electric circuit, while the other which serves as a stay or guy wire, is usually secured to a post in the ground so that it becomes 30 necessary to insure insulation of the one from the other to prevent grounding the circuit. Each of the wires, B and C, terminates in a loop, and these loops are linked together but spaced apart by means of the 35 insulator, A, to avoid contact with each other.

The insulator is provided with a pair of similar guide ways lying in planes at right angles to each other to secure the greatest 40 obtainable spacing of the two loops. Each guide way consists of a pair of parallel grooves, A¹, formed in opposite sides of the outer surface of the insulator body and connected by a third groove, A², extending through the insulator. The bottom portion of the groove, A², is substantially cylindrical and of sufficient size to easily accommodate the wire, B or C, as the case may be; but at its upper or opening portion, A³, the width of the groove is 45 reduced to something less than the diam-

eter of the wire for which it is intended. The purpose of this construction is to prevent the loop of either wire from coming out of the groove, A², into contact with the other loop, if at any time the tension in the wires is slackened. In this way the danger to linemen which has heretofore been present in adjusting or replacing guy wires is greatly reduced, and convenience 55 of handling is increased, since the loops remain in place on the insulator even when all tension is removed from the wires. This result it may be understood, might be accomplished by leaving the narrow portion, A³, of each groove completely closed, thus rendering the portion, A², an aperture merely. But, when this is done there is considerable liability in cold weather that the aperture, A², will become filled with 60 sleet or snow and water so that upon the formation of a solid block of ice in the aperture, the expansion which is characteristic of water in the process of freezing 65 will frequently operate to burst the insulator or at least to crack it, so as to render it unsafe for the proper performance of its function. The provision of the opening, A³, permits this expansion to take place without injury to the insulator, and thus renders 70 it practicable for use in all climates and 75 under all conditions.

I claim:—

1. A strain insulator comprising a body of insulating material having a groove 85 formed in its surface and adapted to receive a wire looped around the insulator, the bottom portion of said groove being wider than the wire which it is intended to receive, and the top or opening portion 90 of the groove being narrower than such wire.

2. A strain insulator comprising a body of insulating material provided with two parallel grooves formed in opposite sides 95 of the body and connected by a transverse groove at one end, said transverse groove being wider toward the bottom than the strain wire which it is designed to accommodate and being narrower than such wire 100 in its upper or opening portion.

3. A strain insulator comprising a body

of insulating material provided with two grooves formed in the surface of said body and lying in directly transverse planes, respectively, a portion of each groove being wider at the bottom than the wire which it is designed to accommodate, and narrower than said wire near the top of the groove.

In testimony whereof I have hereunto set my hand at the city of Peru, Miami county, Indiana this 12 day of August, 1911. 10

OLIVE L. FLETCHER.
